United States Patent

Des. 234,302
Patented Feb. 11, 1975

234,302

MAGNETIC CARD READER-RECORDER OR SIMILAR ARTICLE

Eliot F. Noyes, New Canaan, Conn., assignor to International Business Machines Corporation, Armonk, N.Y.

Filed Apr. 16, 1973, Ser. No. 351,721

Term of patent 14 years

Int. Cl. D14—02
U.S. Cl. D26—5 C

FIG. 1

FIG. 2

FIG. 3

FIG. 4

FIG. 5

FIG. 6

FIG. 1 is a front right perspective view of a magnetic card reader-recorder showing my new design.

FIG. 2 is a right rear perspective view thereof.

FIG. 3 is a left side elevational view thereof.

FIG. 4 is a top plan view thereof.

FIG. 5 is a front elevational view thereof.

FIG. 6 is a rear elevational view thereof.

I claim:

The ornamental design for a magnetic card reader-recorder or similar article, substantially as shown and described.
